UNITED STATES PATENT OFFICE.

JONATHAN D. McCORD, OF HANFORD, CALIFORNIA.

OIL-BURNER.

No. 863,304.

Specification of Letters Patent.

Patented Aug. 13, 1907.

Application filed February 20, 1907. Serial No. 358,379.

To all whom it may concern:

Be it known that I, JONATHAN D. McCORD, a citizen of the United States, residing at Hanford, in the county of Kings and State of California, have invented new and useful Improvements in Oil-Burners, of which the following is a specification.

My invention relates to improvements in oil burning devices; and its object is to provide an oil burner of simple construction for use in stoves, furnaces and the like.

The invention consists of the parts and the construction and combination of parts as hereinafter more fully described and claimed, having reference to the accompanying drawings, in which—

15 Figure 1 is a vertical section showing the construction of my oil burner. Fig. 2 shows a modification of same. Fig. 3 is a perspective view of the base plate and connections.

20 A represents the firebox or combustion chamber of an ordinary stove in which my burner is adapted to fit.

25 2 is a generator preferably of tubular cylindrical form open at the ends and removably clamped in position between the cap 3 and the cup-shaped member 4; the cap 3 and cup 4 having corresponding opposed annular grooves 5 to receive the corresponding ends 30 of the generator tube or pipe 2. These grooves 5 are packed with asbestos or other suitable packing to make them oil and gas tight, and the parts are locked together to inclose a suitable generator chamber inside the tube 2 by suitable means including a clamp screw 6 as will be hereinafter described.

The cup 4 may either be made integral with the end plate or false door 7, as in Fig. 1, or it may be removably carried thereby, as in Fig. 2.

35 The set screw 6 is arranged to bear against the cup 4 and in opposition to some suitable support for the cap 3. The support for the latter and set screw 6 may be the respective studs 8—8' on the base plate 9 as in Fig. 1, or the cap 3 may be supported directly against the back 40 end of the fire-box as in Fig. 2; the set screw in this case being carried by the end plate or false door 7' and adapted to bear against the flange or lugs on the cup 4.

In the construction of the apparatus shown in Fig. 1, I employ a lengthwise corrugated base plate 9 with a 45 rigid upward projection or bracket 8' in which the set screw 6 is threaded. The stud or bracket member 8 which constitute the abutment or support for the rear end of the generator may be rigid with the base plate, or preferably it is channel form in cross section and is 50 removably locked to the base 9 without the use of any screws; by simply dropping one end of the piece 8 into a corresponding socket cast in the top of the base plate. The front of this bracket member 8 is preferably indented as indicated at 10 to receive the central projection or boss 11 on the cap 3. This boss 11 can be 55 fitted into any one of the depressions 10 to accommo-

date the generator to the depth of the firebox and to allow proper tilt of the generator in order to facilitate the flow of the oil therethrough and prevent the oil from accumulating in dangerous quantities in the 60 generator.

The further purpose of supporting the generator at one end by a central projection as 11, is that it enables the generator to have a limited pivotal movement at the rear end, in such fashion that the two end-closures 65 3 and 4 adapt themselves to each other and to the pipe section 2 and insure always a tight joint, irrespective of the inclination of the generator and irrespective of whether the ends of the pipe sections 2 are cut square in the first place or not. The set screw 6 or 6' acts in 70 opposition to the support provided for the projection 11 to clamp the cap, cup and tube together.

If the end plate or false door 7 is made integral with the cup 4 as in Fig. 1, it will ordinarily fit up against the stove just outside of the usual door in the end of the 75 firebox. If this plate or false door is made separate from the cup 4 as in Fig. 2, it will be arranged inside the firebox; the walls of the stove around the usual door opening forming a support for this plate or false door 7' against the action of the set screws 6'. In Fig. 80 2 the walls of the combustion chamber and the plates 7' take the place and fulfil the purpose of the parts 7—8—9 of Fig. 1. The principle of operation, however, of the apparatus shown in both constructions, is 85 the same.

The end plates or false doors 7 are preferably indented or corrugated cross-wise at the top and bottom as shown at 12, so that they can quickly be fitted to a door opening of any size; these end plates being of cast metal, it is a simple matter to break off one or more 90 sections by means of a hammer.

The oil pipe 13 which may be connected with any suitable source of supply, extends underneath the plate 9 and then upward at the back of the firebox to discharge into the rear end of the generator through 95 the cap 3. The gas which is formed in the generator passes out through a pipe 14 on the underside of cup 4 and outside of the firebox.

15 is a gas valve arranged in pipe 14 and regulating the discharge of the generated gas into the combustion 100 chamber A. This valve has a flat or polygonal needle point acting as a reamer in the gas discharge orifice to clear it of all carbon deposits and incrustations, such as tend to accumulate under the circumstances. Suitable air to effect proper combustion is admitted through 105 the air draft openings around the valve.

16 is a firing pan which rests on a sheet of asbestos to separate it from the base plate 9 and protect the underneath oil feed pipe 13; the latter may also be packed in asbestos, and a check-valve 17 may be interposed 110 in this oil pipe to avoid any danger of back flow of the oil. The drip pan is of sufficient size to fit the firebox

and has a neck-portion 16' extending out through an opening in the end plate 7 and beneath the valve so as to catch any drip therefrom. If there is any drip, the same is conducted into the firebox and there consumed.

18 is a baffle or flame spreader which may be of any desired shape or placed in any desired position, and is designed for the purpose of directing the burning gases upward against the generator 2. In operation the oil 10 entering through the feed-pipe 13 is delivered into the generator at the rear end thereof, whence it flows forward and toward the cup 4. If there is a fire in the firebox, the oil is quickly converted into a highly inflammable gas and passes out of the generator through 15 the pipe 14 and valve 15 to be consumed as needed in the fire-box.

When the stove is first lighted up, a small quantity of oil is let into the pan 16 and ignited; when ignited it unites with the current of air entering through the 20 draft openings and the generator is quickly heated up and the generation of gas therein thus begun. The flames spread out and around the generator and thence pass out and over or around the oven in the usual way.

In this apparatus there are no reservoirs to create an 25 alarming flow of gas when highly heated. Complete volatilization takes place in the generator tube, which latter may be easily lifted out and cleaned and replaced by simply operating the set-screw.

These burners may be made in any desired size or 30 shape.

The construction of the apparatus is extremely simple, with very few parts, and all quickly gotten at.

Having thus described my invention, what I claim and desire to secure by Letters Patent, is—

35 1. In an oil burning apparatus, the combination with a firebox, of a generator comprising a tubular section open at the ends, a grooved cap loosely fitting one end of the tube, a grooved cup fitting the opposite end of the tube ends, supports for the cap and cup, said supports comprising 40 means for clamping the cap and cup and tube together to permit a pivotal movement of the generator, means for

delivering the oil into the generator, and means for delivering the gas generated therein into the firebox.

2. In an oil burning apparatus, the combination of a generator comprising a tubular section, a cap loosely fitting 45 one end of the tube, a cup closing the opposite end of the tube, said cap having an external central projection, an abutment for said projection, a set screw bearing against the cup and pressing the cap, cup and tube together to close a generator chamber, a support for said set screw, means for delivering oil into the generator, and means for delivering the gas therefrom.

3. In an oil burning apparatus, the combination of a generator comprising a tubular section, a cap fitting one 55 end thereof, a cup fitting the opposite end of said section, said cap and cup constituting closures for the section, said cup projecting outwardly in line with said section and having its outer end closed, means for supporting the cap, said means comprising a screw member and a support therefor, said screw member adjustably bearing against the cup to clamp the cap, cup and tubular section together, a gas outlet pipe connecting with the chamber of the cup, and a gas valve for controlling the discharge of gas into the combustion chamber.

4. In an oil burning apparatus, the combination of a 65 base plate having vertical standards, a generator supported between said standards, said generator comprising a tubular section, a closure for one end of the section abutting against one of said standards, a closure for the opposite end of the generator, means for clamping the two closures and 70 generator together and permitting of a pivotal movement of said generator, and a set screw threaded in the other standard and abutting against said last-named closure, said retort having suitable inlet and outlet passages.

5. In an oil burning apparatus, the combination of a 75 base plate having vertical standards, and a generator adjustably supported between said standards, said generator comprising a tubular section, a cap closing one end of the section and having a central boss engaging indentations in one of said standards, a cup closing the opposite end 80 of the generator, an end-plate connected with said cup, and a set-screw carried by the other standard and bearing on the cup to clamp the generator together, said generator having suitable inlet and outlet passages.

In testimony whereof I have hereunto set my hand in 85 presence of two subscribing witnesses.

JONATHAN D. McCORD.
